UNITED STATES PATENT OFFICE.

ANDREW W. STEIGER, OF BRIDGEPORT, CONNECTICUT, ASSIGNOR TO UNION TYPE-WRITER COMPANY, OF JERSEY CITY, NEW JERSEY, A CORPORATION OF NEW JERSEY.

TYPE-WRITING MACHINE.

974,445.

Specification of Letters Patent.

Patented Nov. 1, 1910.

Application filed August 6, 1909. Serial No. 511,613.

To all whom it may concern:

Be it known that I, ANDREW W. STEIGER, a citizen of the United States, and resident of Bridgeport, in the county of Fairfield 5 and State of Connecticut, have invented certain new and useful Improvements in Type-Writing Machines, of which the following is a specification.

My invention relates more especially to 10 tabulating mechanism for typewriting machines and its object generally stated is to provide improved devices of the class specified.

More specifically my invention has for one 15 of its objects to provide improved denominational tabulating mechanism.

Another object is to provide improved column selecting mechanism and which may be employed with a comparatively large 20 number of columns.

Another object is to provide key controlled devices which enable the same keys which are employed for denominational tabulating operations to be additionally employed for column selecting operations. 25

Another object is to combine denominational and column selecting mechanism in a much simplified and improved manner.

Other objects will hereinafter appear.

To the above ends my invention consists 30 in the features of construction, combinations of devices and arrangements of parts hereinafter described and particularly pointed out in the claims.

In the present instance my invention is 35 shown as embodied in a front-strike type-writing machine, such parts of the machine as are not essential to a clear understanding of said invention being omitted. It is to be understood, however, that the invention may 40 be adapted to styles of writing machines other than the front-strike machine shown.

In carrying out my invention in the present case, a plurality of column stops are 45 adjusted on a stop bar on the traveling element or carriage to correspond with the columns of the tabular work in hand, and a set of key-controlled denominational stop levers are supported on the frame of the machine. 50 Ordinarily when one of the denominational keys is operated it will effect the release of the carriage and position the associate denominational stop in the path of the column stops so as to arrest the carriage when

the first column stop thereon contacts with 55 the actuated or projected denominational stop. In order to adapt the mechanism for column selecting work a slidable member is provided which is controlled by a key or key bar arranged in proximity to the row 60 of denominational keys and extending lengthwise of said row, said key bar being adapted to control a slidable member which is operated to position certain stop devices so that they will be progressively advanced 65 by coöperation with successive column stops. The extent of advance of said stop devices and the consequent arrest of the carriage is determined by the engagement of certain of said devices with one of the denominational stop levers. The particular stop lever which is moved into position for such engagement will depend on the column 70 at which it is desired to arrest the carriage. When used for column selecting purposes 75 the denominational levers are arrested before they have moved into the path of the column stops and serve as limiting means for the progressively moved column selecting stop devices, certain of said devices co-operating directly with the column stops. The key bar is held or otherwise maintained 80 in the operated position as long as it is desired to employ the mechanism for column selecting purposes. After any particular 85 column has been reached the key bar may be released and the denominational keys employed in the usual way to bring the carriage to any desired denominational position in that particular column. 90

Following is a detailed description of the construction and mode of operation of the exemplification of my invention herein illustrated.

In the accompanying drawings, Figure 1 95 is a top plan view of a front-strike type-writing machine embodying my invention, parts of the machine being omitted and parts broken away. Fig. 2 is a vertical longitudinal sectional view of the machine with 100 parts omitted and parts broken away. Fig. 3 is a rear view partly in vertical section, showing details of my invention. Fig. 4 is a view corresponding to Fig. 3 but showing some of the parts in different relations and 105 omitting other parts shown in said Fig. 3. Fig. 5 is a perspective view of the tabulator key system. Figs. 6 and 7 are views similar

to Fig. 3 but are drawn on an enlarged scale and show the parts in different stages of operation. Fig. 8 is a fragmentary sectional view corresponding to Fig. 3 and 5 showing various parts of Fig. 1 on an enlarged scale. Fig. 9 is a side view of certain of the parts as they appear in Fig. 7. Fig. 10 is a sectional view taken on a plane represented by the dotted line $x-x$ in Fig. 6 10 and looking in the direction of the arrows at said line.

Referring first to Figs. 1 and 2, the body 1 of the main frame is surmounted by a top plate 2 formed with a depression 3. Key 15 levers 4 are fulcrumed at 5 in rear of the base of the main frame, each key lever being connected as by a link 6, a bell crank 7 and a second link 8 with a type bar 9 pivoted on a hanger 10 secured to a vertically disposed 20 segmental support 11. Only one type bar is shown but it is to be understood that a complete set of type bars are provided, arranged in an arc of a circle on the segment 11, the type ends of said type bars normally resting 25 on a segmental type rest 12. The actuating mechanisms of the type bars are provided with restoring springs (not shown) and when each type bar is actuated it will co-operate with the front face of a cylindrical 30 platen 13 rotatably supported on the end plates 14 of a traveling element, carrier or carriage which further comprises a slide bar 15 at the ends whereof rise the end plates 14. The front and rear faces of the slide bar 35 are formed with longitudinally extending grooves which receive anti-friction balls 16, said balls also co-operating with fixed track ways 17 suitably secured at the front and rear sides of the depression 3. Levers 18 40 pivoted at 19 to the ends of the slide bar 15 support at their lower ends a feed rack 20, the upper ends of said levers co-operating with springs 21 which serve to constantly press the feed rack toward a feed pinion 22 45 and normally to maintain said feed rack in mesh with said pinion. The pinion 22 is secured to the upper end of a vertical shaft 23 which passes through the bottom of the depression 3, the lower end of said shaft 50 bearing in a stationary bar or bracket 24. Near its lower end the shaft 23 carries a toothed carriage feeding or escapement wheel 25 with which co-operate feed dogs 26 mounted on a rocker 27 secured to a rock 55 shaft 28 pivoted on an arm 29 projecting forward from the bracket 24. Arms 30 extend forward from the rock shaft and carry depending links 31 which support a universal bar 32 underlying the key levers. 60 The carriage is constantly urged leftward by a spring drum 33 pivoted on a bracket 34 depending from the portion 3 of the top plate, said spring drum being connected with the carriage by a strap or cord 35.

65 It will be understood that when one of the

printing key levers 4 or the usual space bar or key is operated it will actuate the universal bar 32, causing the carriage feeding devices to co-operate to permit a letter space feed movement of the carriage under the 70 pull of the main spring. It will further be understood that the carriage is or may be equipped with the usual or suitable paper feeding devices including a paper deflector or guide 36 and a feed roller 37; that the platen is 75 or may be associated with suitable line spacing devices comprising a ratchet wheel 38, a pawl 39 and a hand-operated lever 40; and that suitable inking devices preferably comprising an ink ribbon and means for feeding 80 and controlling it are employed although not shown herein.

The tabulating mechanism comprises a stop bar 41 arranged in rear of the platen and extending lengthwise thereof, said stop bar being secured at its ends to the end plates 14. The front and rear faces of the stop bar are preferably notched as indicated at 42 to provide teeth a letter space distance apart. Adjustably supported on the stop 85 bar 41 are column stops 43 which are or may be plate-like in form and cut out to fit between the teeth of the stop bar 41. Each stop plate 43 is provided at its rear with an extension or depending stop portion 44 90 which is the stop proper. A set of angular levers 45 are provided to co-operate with the column stops in different ways. The vertically disposed portions of said levers pass upward through an opening 46 in the top plate and terminate in stop portions 47. Said vertical portions extend downward parallel with each other and pass between the key levers 4 and then gradually curve 95 forward into the horizontal portions of said levers. The levers are fulcrumed through their horizontal portions on a rod 48 which extends transversely of the key levers below the same and is secured in the sides of the base. The forward end portions of the levers 45 are reduced as indicated at 49 and are received in holes in vertical key stems 50, said key stems being guided in openings in stationary guide plates 51 and 52 and terminating at their upper ends in buttons or finger keys 53 which may be provided with suitable indicating marks on their upper surfaces. As shown in the drawings there are ten tabulating keys 53 and ten associate 100 levers 45. The keys 53 are arranged in a bank or row in rear of the regular keyboard and above the last row of said keyboard. Said keys 53 as herein shown are oblong and are spaced a convenient distance apart. From their points of connection with the 105 key stems 50 the horizontal portions of the levers 45 extend rearward and at the same time incline inward toward the middle of the machine so that the rear or vertically disposed portions of the levers 45 lie com- 110

115

120

125

130

paratively close together (see Fig. 5). The upper ends or stop portions 47 of the levers 45 are guided in slots 54 formed a letter space distance apart in a guide plate 55 which is suitably secured to the rear portion of the top plate 2 over the opening 46. Normally the stop portions 47 are maintained at the rear ends of the slots 54 and below the plane of the stop portions 44 by springs 56, each spring being secured at one end to one of the levers 45 and at the other end to a stationary bracket 57.

It will be understood that when one of the keys 53 is depressed it will swing the associate lever 45 on its pivot and raise the stop portion 47 upward and forward so that if the movement is not interfered with said stop portion will be brought into the path of the extensions or stops 44, being thereby adapted to arrest the carriage in a particular denominational position.

Means are provided for automatically releasing the carriage from its step-by-step feeding devices through the operation of the levers 45. Said means may comprise a retarding contrivance which consists in part of a casing 58 pivotally supported at 59 on a bracket 60 depending from the depressed part 3 of the top plate. Retarding contrivances of any suitable character are arranged in the casing and are adapted to be operated from a shaft 61 which extends upward, bearing in a hub 62 integral with the casing 58. Said shaft carries outside the casing a pinion 63 which normally lies in front of and out of mesh with the feed rack 20 but is adapted, when the casing 58 is swung rearward, to force said rack out of mesh with the feed pinion 22 and against the pressure of the springs 21, thus releasing the carriage and permitting it to run under control of the retarder. The means for swinging the casing and pinion 63 rearward comprise a link 64 pivotally connected at its upper end with the casing 58 forward of the pivots 59. Said link extends downward and is pivotally connected at its lower end with an arm or extension 65 extending rearward from the pivot rod 48 and integral with an arm 66 extending forward from said pivot rod. As shown in Fig. 5 the arm 66 lies at the right of the set of levers 45. A similarly forwardly extending arm 67 is pivoted on the rod 48 at the left of the levers 45. The two arms 66 and 67 are connected by a release bar 68 which underlies the levers 45 near their forward ends and is adapted to be operated when any one of said levers is depressed so as to raise the link 64 and cause the pinion 63 to release the carriage. The retarder may be dispensed with and the carriage may be released for tabulating purposes in any other manner which may be preferred.

65 From one aspect of my invention the tabu-

lating mechanism thus far described constitutes what is commonly termed a denominational or decimal tabulator and is capable of doing ordinary denominational tabulating work. After one or more column stops 70 43 have been properly located in the rack 42 any one of the tabulating keys 53 may be pressed to move its associate lever 45 into the path of the column stops and to release the carriage. When released the carriage 75 will move leftward under the pull of its main spring and will continue to move until the first column stop comes in contact with the actuated or projected denominational stop 47. When the operative key 53 is released all the parts will return to normal position and the carriage by the coöperation of the tabulating stops will thus be located with reference to the printing point in accordance with the tabulating key 53 which 80 has been selected and operated, this location being in the first column and at a pre-determined denominational position therein.

It will be understood that the tabulating mechanism as thus far described will operate always to bring one of the stops 47 into coöperation with the first column stop that has to pass the set of denominational stops and that each column as determined by the location of the column stops 43 before beginning work will be brought to printing position in regular sequence. To pass columns in which it is not desired to make entries it is necessary with the mechanism as thus far described to operate one of the 100 tabulator keys 53 as many times as there are columns to be passed, thus effecting a corresponding arrest of the carriage at each of these intervening columns. In order to do away with the loss of time thus occasioned, a column selecting mechanism is provided. The column selecting mechanism in the present case comprises key-controlled devices which are preferably associated with the tabulating mechanism above described 110 so as to enable the keys 53 to be at will operated to release the carriage and arrest it at the beginning of predetermined columnar positions, intervening columns being skipped or passed. Said devices are in part supported on an angular bracket or flanged plate 69 which is suitably secured to the under side of the rear portion of the top plate 2 and extends downward therefrom. Said devices comprise a stop member or slidable plate 70 120 which is formed with a longitudinal slot 71 through which pass shouldered screws 72, said screws as shown in Fig. 10 screwing into the bracket 69 and providing bearings on which the plate 70 may slide longitudinally back and forth. Normally the left-hand end (viewed from the rear) of the slot 71 is maintained in contact with the left-hand screw 72 by a coiled spring 73, one end of which is secured to the plate and the 125 130

other end to a pin 74 depending from the top plate 2. The under side of the plate 70 is provided with a series of saw teeth 75 which are a letter space distance apart and 5 as viewed from the rear the left-hand end of the plate 70 is reduced in width and bent rearward at right angles to provide a lip or stop 76.

With the parts in normal position as 10 shown in Fig. 3 the contact face of the stop 76 is in the plane of the outer face of the adjacent lever 45 just under the top plate. It will be understood from Fig. 2, which 15 shows a side view of the parts in normal position, that the levers are not normally in the path of the stop 76; but the keys 53 may be depressed to bring the levers 45 in the path of the stop. Pivotally supported on the screws 72 are parallel arms 77 and 78, 20 said arms being arranged between the rear face of the plate 71 and the head of the screws 72 as will be understood from Fig. 10. The arms extend upward through an opening or slot 2^a in the top plate. Pivotally supported at 79 at the upper ends of 25 the arms 77 and 78 is a stop member 80 which is channeled or U-shaped to embrace the supporting arms. The inner end of the stop member 80 is provided with an up- 30 turned lug or finger 81 which serves as a column selecting stop coöperating directly with the column stops 43 as presently to be explained. Ordinarily, however, the stop member 80 is depressed as shown in Fig. 4 35 so that the column selecting stop 81 lies below the planes of the column stops proper 43 and cannot be engaged by them. The means for depressing and raising the stop member 80 and stop 81 will be explained 40 later on.

Integral with the arm 78 and below the pivot screw 72, is an arm 82, the arms 78 and 82 constituting a lever which is slightly angular. Pivoted at 83 to the lower end of 45 the lever 78, 82 is an arm or pawl carrier 84 provided with a pawl tooth 85 which is adapted to coöperate with the teeth 75 on the slide 70. The pawl tooth 85 is constantly urged upward to engage with the 50 teeth 75 by a coiled spring 86 secured at one end to a pin 87 on the pawl arm 84 and at the other end to a pin 88 projecting rearward from the bracket 69 through the slot 71. A detent pawl 89 is pivoted at 90 to the 55 bracket 69 and is maintained in engagement with the teeth 75 by a leaf spring 91. The stop member 80 is adapted to be raised into operative position from normal position by means which comprise a roller 92, said roller 60 being pivoted at 93 to the upper end of an arm 94 which in turn is pivoted at 95 to a plate-like lifter 96, said lifter being provided with vertical parallel slots 97 through 65 which pivot screws 98 pass into the bracket 69, said screws coöperating with said slots to

guide the lifter upward and downward on the supporting bracket when actuated. The roller 92 co-acts with the outer or, as viewed from the rear, right-hand face of the lever 78, 82 and is constantly maintained in engagement with said lever by a coiled spring 99 which is secured to pins 100 and 101 projecting rearward respectively from the arm 94 and the lifter 96. The lifter is provided with an extension 96^a which, as viewed from the rear, extends leftward in front of and across the path of the levers 45 and is provided with a rearwardly extending shelf or lip 96^b which is adapted to co-act with said levers 45 to limit their movements. Said levers 45 are, however, provided with cut-outs or slots 102 which when the stop lip 96^b is positioned as in Figs. 2 and 8, will embrace the stop lip when actuated and permit a full and complete movement of the levers 45. 85 The slide 96 is provided with a downwardly extending screw socket 103 which receives the threaded upper end of an arm 104, said arm extending downward and being pivotally connected at 105 with the rear arm of a lever 106 which lever is fulcrumed on the rod 48. The lever 106 is arranged at the left-hand side of the set of levers 45 and between said levers and the arm 67 (Fig. 5). At the opposite side of the set of levers 45 is 90 an arm 107, said arm being pivoted on the rod 48 and extending horizontally forward therefrom. Pivotally connected with the forward ends of the levers 106 and arm 107 are upwardly extending arms or stems 108 100 which are guided through openings in the guide plate 52 and are connected at their tops by a bar or key 109 which is arranged at the rear of the row of keys 53 and extends longitudinally thereof, so that while holding 105 the bar 108 in operated position, the operator may actuate with the same hand or finger any one of the keys 53. Normally the bar 109 is maintained on a level with the row of keys 53 by a coiled spring 110, one 110 end of which is secured to the arm 107 and the opposite end to the guide plate 52 (Fig. 2). Said spring also serves to normally maintain the lifter 96 in its lower or inoperative position as illustrated in Figs. 2 and 4. 115 The lifter 96 is provided with a T-shaped extension comprising an upwardly extending arm or stem 111 which is also off-set rearward from the body of the lifter to clear other parts of the mechanism. At its top the 120 stem is provided with oppositely off-set fingers 112 and 113, the finger 112 coöperating with the pin 87 to control the pawl arm 84 as presently to be described; while the finger 113 is adapted to coöperate with a pin 125 114 extending rearward from the detent pawl 89 to control said detent pawl. Integral with the bracket 69 and underlying the 130 slidable plate 70 is a lug 115 formed with two stop faces 116 and 117, the stop face 117 be-

ing horizontal and the stop face 116 being inclined leftward from the vertical as viewed from the rear.

Suppose that with the carriage at the beginning of the line of writing and with the parts in normal position, that is, with the lifter 96 lowered as in Fig. 4, it be desired to skip or pass several columns and to write in, say, the third column from the left-hand margin. It is to be noted that at this time with the slide 96 down as in Fig. 4, the finger 113 will be in engagement with the pin 114 so that the detent pawl 89 will be inoperative on the teeth 75 while the pawl tooth 85 will be maintained by the stop face 117 in inoperative position. Furthermore the arm 94 will be drawn over by the spring 99 and the roller 92 will be pressed against the lever arm 82 so as to maintain the stop 81 down in inoperative position. The spring 86 assists somewhat to perform the last named function. As a preliminary to skipping or passing columns the operator first presses the bar or key 109 in order to bring the column selecting mechanism into operation. The depression of the bar 109 operates to swing upward the rear arm of the lever 106 and raise the arm 104, said arm in turn raising the lifter 96 which slides upward over the bracket 69 from the Fig. 4 to Fig. 3 position, being arrested in the latter position by the engagement of the lower ends of the slots 97 with the stems of the screws 98. During the upward movement of the lifter the finger 113 will release the pin 114 and the spring 91 will force the detent pawl 89 into engagement with the teeth 75. At the same time the roller 92 will slide upward over the edge or face of the lever 78, 82 and after it passes the fulcrum of said lever and engages with the upper arm 78 will swing said arm leftward as viewed from the rear. This movement of the arm 78 will cause a corresponding movement of the arm 77 and will lift the stop member 80 and stop 81 into operative position as shown in Fig. 3. During this movement of the arms and the stop member the lower lever arm 82 will swing rightward and will withdraw the pawl tooth 85 from the stop face 117. As soon as the pawl tooth disengages from the stop face the spring 86 will draw said pawl tooth upward into engagement with the rack teeth 75. Furthermore, the upward movement of the lifter elevates the extension 96^a carrying the stop lip 96^b upward so that said stop lip is raised out of the path of the notches 102 in the upright arms of the levers 45 and so that when actuated said notches cannot engage with the stop lip 96^b. Maintaining the bar 109 in depressed position the operator next depresses the third key 53 from the left-hand end of the row since it is desired to skip the preceding columns and write in the

third column. The depression of the key 53 operates to swing the associate lever 45 on its fulcrum, lifting the upright arm of said lever upward and forward until the front edge of said lever above the slot or notch 102 contacts with the stop or lip 96^b. As shown in Fig. 9 this movement advances the lever arm into the path of the stop lip 76 but does not permit the stop 47 to rise into the path of the column stops. Concurrently with the advance of the actuated lever 45 to the Fig. 9 position the carriage will be released as has been heretofore described and will be drawn leftward by the main spring, bringing the first column stop 43 into engagement with the column selecting stop 81. After such engagement and during the further advance of the carriage, the first column stop will operate on the column selecting stop 81 and will swing the stop member 80 rightward as viewed from the rear, causing a corresponding leftward movement of the pawl member 84, this movement of the pawl member continuing until its end contacts with the stop face 116 which serves to limit the movement and jam the pawl tooth 85 into the rack 75.

The parts are so proportioned that when the arrest of the pawl arm takes place the stop member will have been swung sufficiently far to the right and downward to lower the stop 81 out of the path of the first column stop and permit said column stop to slide over the top of said stop 81 and continue its advance. During the leftward movement of the pawl arm 84 the pawl tooth 85, being in engagement with the first of the rack teeth 75 as shown in Fig. 3, will advance the slide plate 70 one step leftward, overcoming the spring 73. After the first column stop has released the stop 81 the stop member 80 will be restored to the Fig. 3 position by the spring-pressed roller 92, causing a retraction of the pawl arm 84, the pawl 85 slipping back over the contiguous rack tooth 75 and engaging with the second tooth space from the left. The retraction of the slide plate 70 will, however, be prevented from the detent pawl 89, said pawl serving to retain said slide plate in its advanced position one step leftward from normal position. The continued movement of the carriage will bring the second column stop 43 into engagement with the column selecting stop 81 and will cause the steps as above outlined to be repeated so as to advance the slide plate 70 an additional space or step, thus bringing the stop lip 76 on said slide plate into contact with the vertical arm of the projected lever 45 which lies in its path. Fig. 6 shows the parts in the last described relationship just prior to the release of the stop 81 by the second column stop. When said second column stop releases the stop 81 said stop 81 and connected parts will be re-

stored to the position shown in Fig. 7, the pawl tooth 84 being retracted to engage with the third space between the rack teeth 75, counting from the left and as viewed from the rear. The last step of the advance movement of the carriage brings the third column stop into engagement with the column selecting stop 81 as shown in Fig. 7 and causes the arrest of the carriage because the column selecting stop is prevented from yielding to the third column stop by reason of the engagement of the stop face 76 with the projected lever 45. This will be understood from a consideration of Fig. 7 from which it will be noted that the slide plate 70 on which the stop plate 76 is rigid is held from advance; that consequently the rack teeth 75 cannot move; that by reason of the engagement of the pawl tooth 85 with said rack teeth the pawl arm is held from movement leftward; and that said pawl arm maintains the lever 78, 82 from movement, said lever, of course, holding motionless the stop member 80 and stop 81.

When the carriage is arrested the key 53 and bar 109 may be released. The release of the key 53 permits the restoration of the parts controlled thereby including the lever 45 and the carriage releasing devices to normal position as shown in Fig. 2; while the release of the bar 109 permits the retraction of the lifter 96 to the Fig. 4 position. During the retraction or downward movement of the lifter the finger 113 will operate on the pin 114 to swing the detent pawl 89 out of the rack 75 and the finger 112 will engage the pin 87 and swing the pawl arm 84 down out of the rack 75, bringing the pawl tooth 85 below the stop face 117 so that when the roller 92 begins to act below the fulcrum of the lever 78, 82 the pawl arm 84 will be moved leftward and the pawl 85 will be brought under the stop face 117. As soon as the pawls 89 and 85 disengage from the rack teeth 75 the slide plate 70 will be retracted to the normal position shown in Fig. 4 by the spring 73.

It will be noted that the operation above outlined causes the carriage to be released and to be advanced and arrested at the beginning of the third column, the first and second columns preceding being skipped or passed. If, now, it be desired to write at a particular denominational position in the third column, the operator has only to actuate the desired key 53 to cause the carriage to be released and arrested in the corresponding denominational position in said third column. In other words, my present invention enables intervening columns to be skipped at pleasure and the carriage to be released and subsequently arrested at the beginning of any desired columnar position, the number of columns skipped being only limited by the number of the keys 53. The

column selecting mechanism is brought into operation by the depression of the bar 109 and while holding said bar depressed any of the keys 53 may be operated to select corresponding columns. After this arrest of the carriage at such selected column the release of the bar 109 again permits the keys 53 to be operated for denominational purposes. The next succeeding column stop will co-operate with the levers 45 to determine denominational positions in the selected column.

It is my observation that in most cases of tabulating work involving a large number of columns, such work, for example, as train sheets or the like, it is desired to begin writing the data in most of the columns at the beginning of such columns and it is only in comparatively few of the columns that it is desired to select a particular denominational position. The present form of my invention is particularly adapted to this class of work in which from time to time it is necessary to skip one or more columns and begin writing at the initial position in a subsequent column. In such case all that it is necessary to do with my invention in use is to count from the column in use to the column in which it is desired to write next and then after actuating the bar 109 to operate the corresponding key 53. It will be understood that in each instance in order to determine the proper key 53 to operate, it is necessary to count the number of columns from the one in use to the desired column and not the number from the beginning or left-hand side of the sheet.

It is to be noted that by my present invention I combine a plurality of column stops and a single co-operating stop, the stops 105 when co-operating yielding one to the other, with means for preventing such yielding when said single stop co-operates with a predetermined stop of said plurality of stops; that the yielding in the present instance 110 takes place on the part of the single co-operating stop which is adapted to be moved by one or more of the column stops out of their own paths during the run of the carriage, each of such movements of the single 115 stop which may be termed the column selecting stop, operating to step a slideable stop member toward its point of final arrest so that eventually when the selected column stop comes along, the single stop will not yield but will operate to prevent further movement of the carriage; that I provide a stop combined with a plurality of stops cooperative therewith for denominational purposes, said plurality of stops being co-operative with still another stop for column selecting purposes; and that said plurality of stops, which in the present case are on key controlled levers, co-operate at one time directly with the column stops for denomina- 120 125 130

tional purposes and at other times with interposable stop devices in order to select particular columns in which to arrest the carriage, any intervening columns being 5 skipped or passed.

Where in the sub-joined claims a single stop or a single coöperating stop or the like is referred to, it is to be understood that the term means a stop having a single stopping 10 or arresting face in contradistinction from a stop member which, although it may be a single piece, is provided with a plurality of stop faces which are operative at different times.

15 Various changes may be made without departing from the spirit and scope of my invention.

What I claim as new and desire to secure by Letters Patent, is:—

20 1. In tabulating mechanism for typewriting machines, the combination of a plurality of stops, a single coöperating stop, the stops when coöperating yielding one to the other, and means for preventing such yielding 25 when said single stop coöperates with a predetermined stop of said plurality of stops.

2. In tabulating mechanism for typewriting machines, the combination of a plurality of stops, a single coöperating stop yieldable 30 to said plurality of stops, and means for preventing said single stop from yielding to a predetermined stop of said plurality of stops.

3. In tabulating mechanism for typewriting 35 machines, the combination of a carriage, a set of column stops, a single column selecting stop coöperative therewith and yielding to certain of said column stops, and means for holding said selecting stop rigid to co- 40 operate with a predetermined column stop to arrest the carriage, intervening column stops being skipped or passed.

4. In tabulating mechanism for typewriting 45 machines, the combination of a carriage, a plurality of column stops adjustably arranged thereon, a single column selecting stop on the frame of the machine, said selecting stop being yieldable to certain of said column stops when the carriage is re- 50 leased, and means for preventing said single stop from yielding to a predetermined column stop so as to arrest the carriage in a predetermined columnar position.

5. In tabulating mechanism for typewriting 55 machines, the combination of a plurality of stops, a single coöperating stop yieldable to said plurality of stops, and means controlled by a plurality of keys for preventing said single stop from yielding to a predeter- 60 mined stop of said plurality of stops.

6. In tabulating mechanism for typewriting 65 machines, the combination of a plurality of stops, a single coöperating stop in the path of said plurality of stops, and means for causing said single stop to co-act with a

predetermined one of said plurality of stops to arrest the carriage, any intervening stops of said plurality of stops being skipped or passed.

7. In tabulating mechanism for typewriting 70 machines, the combination of a set of column stops, a single column selecting stop in the path of said column stops, and means for causing said single stop to co-act with a predetermined column stop to arrest the carriage in a selected columnar position, any intervening column stops being skipped or passed.

8. In tabulating mechanism for typewriting 80 machines, the combination of a carriage, column stops adjustable thereon, a single column selecting stop in the path of said column stops, and means for causing said single stop to co-act with a predetermined column stop to arrest the carriage in a 85 selected columnar position, said single stop permitting any intervening column stops to pass by it.

9. In tabulating mechanism for typewriting 90 machines, the combination of a plurality of stops, a single coöperating stop in the path of said plurality of stops, and means controlled by a plurality of keys for causing said single stop to co-act with predetermined ones of said plurality of stops to arrest the 95 carriage, any intervening stops of said plurality being skipped or passed.

10. In tabulating mechanism for typewriting 100 machines, the combination of a stop, a plurality of stops coöperative therewith for denominational purposes and another stop coöperative with said plurality of stops for column selecting purposes.

11. In tabulating mechanism for typewriting 105 machines, the combination of a set of column stops, a plurality of stops coöperative therewith for selecting denominational positions in columns defined in part by said column stops, and another stop coöperative with said plurality of stops for 110 column selecting purposes.

12. In tabulating mechanism for typewriting 115 machines, the combination of a set of column stops, a plurality of stops coöperative therewith to obtain predetermined denominational positions in the columns determined in part by said column stops, and another stop coöperative with said column stops and also with said plurality of stops to select particular columns, any intervening 120 columns being skipped or passed.

13. In tabulating mechanism for typewriting 125 machines, the combination of a set of column stops, key controlled levers coöperative therewith to obtain predetermined denominational positions, and another stop coöperative with said levers to select predetermined columns in conjunction with said column stops.

14. In tabulating mechanism for type- 130

- writing machines, the combination of a set of column stops, key controlled stop levers coöperative directly therewith to obtain predetermined denominational positions in columns, and another stop movable to coöperate directly with said levers to assist in selecting particular columns in which to write.

15. In tabulating mechanism for type-writing machines, the combination of a stop, a plurality of stops coöperative directly therewith for denominational purposes and another stop movable into position to coöperate directly with said plurality of stops to assist in determining particular columns in which to write.

16. In tabulating mechanism for type-writing machines, the combination of a stop, a plurality of stops coöperative directly therewith for denominational purposes, other stops, and means for interposing said other stops between the first recited stop and said coöperative stops to select particular columns in which to write.

17. In tabulating mechanism for type-writing machines, the combination of a stop, a plurality of stops coöperative directly therewith for denominational purposes, limiting means for preventing direct coöperation between said stop and said plurality of stops, and other stops coöperative with said first recited stop and said plurality of stops to select predetermined columns.

18. In tabulating mechanism for type-writing machines, the combination of column stops, a plurality of denominational stops coöperative with said column stops, a stop movable to prevent coöperation between said column stops and said denominational stop, a column selecting stop movable into the path of said column stop, and a progressively movable stop coöperative with said denominational stops to assist in selecting predetermined columns.

19. In tabulating mechanism for type-writing machines, the combination of a set of column stops having a common path of movement, a single column selecting stop normally inoperative, means for moving said column selecting stop into the path of said column stops, and means for causing said single stop to co-act with a predetermined column stop to arrest the carriage in a selected column.

20. In tabulating mechanism for type-writing machines, the combination of column stops having a common path of movement, a single column selecting stop movable bodily into and out of the path of said column stops, and means for causing said single stop to co-act with a predetermined column stop to arrest the carriage.

21. In tabulating mechanism for type-writing machines, the combination of a set of column stops, a stop carrier, a column selecting stop on said carrier, pivoted arms supporting said carrier, and means for controlling said arms to cause said selecting stop to operatively engage with predetermined column stops.

22. In tabulating mechanism for type-writing machines, the combination of column stops, coöperating denominational stop levers, and column selecting devices including a progressively movable stop co-active with said levers.

23. In tabulating mechanism for type-writing machines, the combination of column stops, coöperating denominational stop levers, column selecting devices including a slidable member co-active with said levers, and means for progressively advancing said member.

24. In tabulating mechanism for type-writing machines, the combination of column stops, coöperating denominational stop levers, column selecting devices including a toothed slidable stop member co-active with said levers, and means including a pawl operative to progressively advance said member.

25. In tabulating mechanism for type-writing machines, the combination of column stops, a single column selecting stop in the path of said column stops and yieldable thereto, and means for preventing said selecting stop from yielding to a predetermined column stop, said means including a progressively movable stop member.

26. In tabulating mechanism for type-writing machines, the combination of column stops, a column selecting stop in the path of said column stops and yieldable thereto, means for preventing said selecting stop from yielding to a predetermined column stop, said means including a toothed slidable plate, and a pawl operative to advance said plate step-by-step.

27. In tabulating mechanism for type-writing machines, the combination of a set of column stops, a column selecting stop, selecting stop mechanism for controlling said stop, said mechanism comprising a key controlled lifter, and a spring pressed slidable member.

28. In tabulating mechanism for type-writing machines, the combination of a single set of column stops, a set of coöperating denominational stops, a set of keys controlling said denominational stops, and hand controlled column selecting devices, said keys operating on said hand controlled devices to select predetermined columns after the prior setting of said devices by hand.

29. In tabulating mechanism for type-writing machines, the combination of a single set of column stops, denominational stop mechanism, and column selecting mechanism settable by hand, both said mechanisms being operative by a single set of keys

after said column selecting mechanism has been set, each of said keys being operative to select a single denominational position in any one of the columns and being also operative to determine the arrest of the carriage in a particular columnar position, intermediate columns being skipped or passed.

30. In tabulating mechanism for type-writing machines, the combination of a single set of column stops, a set of coöperating denominational stops, a set of keys controlling said denominational stops, column selecting devices controlled by a finger key

in the vicinity of said set of keys, said set of keys operating said column selecting devices to select predetermined columns after the actuation of said finger key.

Signed at the borough of Manhattan, city of New York, in the county of New York, and State of New York, this 5 day of August, A. D. 1909.

ANDREW W. STEIGER.
